UNITED STATES PATENT OFFICE

THOMAS T. GREENE, OF COLLINGSWOOD, NEW JERSEY, ASSIGNOR TO VICTOR TALKING MACHINE COMPANY, A CORPORATION OF NEW JERSEY

RECORD HOLDER FOR TALKING MACHINES

Application filed September 19, 1927. Serial No. 220,561.

This invention relates to cabinets and more particularly to talking machine cabinets provided with record holding means.

It is an object of this invention to provide a cabinet with novel means for holding talking machine records of the disk type.

Another object of this invention is to provide novel means adapted to be housed in the lid or cover of the cabinet for holding talking machine records.

Another object of this invention is to provide a record holder adapted to be housed in the lid of a talking machine cabinet and means whereby, as the lid is moved to open position, the holder will be moved relatively to the lid to render the records therein accessible.

Another object of this invention is to provide novel record holding means adapted to be mounted in the lid of a talking machine cabinet whereby, as the lid is moved to open position, the record holder will be tilted outwardly relative to the cover to render the records accessible, and when the lid is moved to closed position, the holder will be automatically moved into the lid.

Another object of this invention is to provide novel means for pivotally mounting a holder in the lid of a cabinet.

One embodiment of the invention is shown in the accompanying drawings, but it is to be expressly understood that the drawings are for purposes of illustration only and are not designed as a definition of the limits of the invention, reference being had for this purpose to the appended claims.

In the drawings—

Fig. 1 is a front elevation illustrating a record holding means constituting the subject matter of the present invention mounted in the lid of a cabinet, a portion of the body of the cabinet being shown in section;

Fig. 2 is a side elevation partly in section of the structure shown in Fig. 1.

The record holder embodying the present invention is particularly adapted for use in combination with a cabinet of a portable talking machine, the body 3 of said cabinet being provided with a hinged cover or lid 4. Se-

face of the rear wall of said lid is a strip or bar 5 which is preferably formed of wood. The lower front corner of bar 5 is preferably beveled, as indicated at 5^a, to facilitate the insertion of screws 6 for securing the strip to the cover. Glue may also be used to coat with screws 6 for maintaining the strip in position in the cover.

Means are provided for pivotally connecting a record holder to strip 5. For this purpose angular brackets 7 are secured to the outer face of the strip closely adjacent the inner surface of the top of the lid, the outwardly projecting portions of each of the brackets 7 being suitably apertured to receive pivot pins 8. The latter have pivotal engagement with hinge members 9 and 10 that are secured to the opposite side walls of an open-ended box-like member 11 constituting the record holder.

The hinge members 9 and 10, which may be secured to the record holder 11 in any suitable way, as by means of screws 12, preferably extend slightly below the bottom or closed end 13 of the record holder and the pivot pins 8 engage these projecting portions of the hinge members.

In the form shown, the record holder comprises front and rear walls 14 and 15 respectively and suitably secured between said side walls, as by means of glue, for example, is a U-shaped member 16, the outer surfaces of which constitute the end walls and bottom wall 13 of the holder. The U-shaped member, if desired, may be formed of wood, the bight of the U being of the proper shape and size to readily receive therein the largest record which it is desired to carry and the arms of the U extending substantially flush with the outer edges of front and rear walls 14, 15. Preferably, the inner surface of the U-shaped member 16 is covered with a yielding material such as felt 17 for preventing damage to the edges of the records.

Means are provided for insuring that the upper open end of the holder will be tilted outwardly relative to the cover to render the records readily accessible when said cover is in open position, and to insure that the holder will be automatically moved to and retained in a position such that its front and rear

walls 14 and 15 are substantially parallel to the top of the cover 4 when said cover is in closed position. For this purpose either one of the hinge members 9 is provided with a projecting arm portion 18 which carries on its outer end a transversely extending pin 19 which is adapted to extend through a slot 20 formed in a bracket 21 that is secured in any suitable manner to the inner surface of the rear wall of cabinet 3. The slot is so formed that the lower portion of the same curves about the axis of the hinges 22 for securing the cover or lid 4 to the cabinet 3, but the curvature of slot 20 increases towards the upper end thereof, the radius of curvature of this portion of the slot being less than the radius of curvature of the lower portion thereof.

When the lid or cover is moved to open position, holder 11 is correspondingly moved therewith, but because of the curvature of slot 20 and the engagement there with pin 19, the upper open end of holder 11 has its movement retarded relative to the cover so that it assumes an angular position with respect thereto, said open end being tilted outwardly clear of the side walls of the cover whereby the records are readily accessible. When the cover is moved to closed position the movement of pin 19 along slot 20 serves to return the holder into housed position in the cover with the front and rear walls of said holder substantially parallel to the top of the cover, and the holder is retained in this position when the cover is closed, due to the engagement of pin 19 with the side of slot 20.

There is thus provided novel means for holding records in a talking machine cabinet. The holder is adapted to be housed in a cover, thereby conserving space, and means are associated therewith for rendering the records readily accessible when the cover is moved to open position. The holder is also moved automatically into the cover when the latter is closed, and the front wall of the cover coacts with the holder to prevent the records from falling out of the latter. The device is also simple in construction and may be readily and inexpensively manufactured and installed.

While only one embodiment of the invention is illustrated and described herein, various changes in the details of construction will readily suggest themselves to those skilled in the art. For example, both of the hinged members 9 and 10 may be provided with pins 19 to coact with a pair of slotted brackets 21. The form of the hinge for securing the holder to the lid may be varied and in certain instances it may be desirable to eliminate the use of the strip or bar 5. Reference will therefore be had to the appended claims for a definition of the limits of the invention.

What is claimed is:

1. In combination with a cabinet having a

hinged cover, a holder adapted to be housed in said cover, pivot members securing said holder to the cover, a bracket having an arcuate slot therein secured to the cabinet, the curvature of said slot increasing toward the upper end thereof, and a pin operatively connected to said record holder and cooperating with the slot in said bracket.

2. In combination with a cabinet having a hinged cover, an open-ended box-like holder mounted in said cover, means pivotally connecting said holder to said cover, said means including an L-shaped member, a pin secured to one arm of said L-shaped member, and a slotted bracket secured to the body of the cabinet and cooperating with said pin.

3. The combination of a talking machine cabinet having a hinged cover, an open-ended box-like member for holding records adapted to be housed in said cover, pivot members mounting said record holding member in said cover, a bracket secured to the cabinet and having a slot therein which increases in curvature towards one of its ends, and a pin operatively connected to said record holding member and cooperating with said slot to produce relative movement between said record holding member and said cover as said cover is opened and closed.

4. The combination of a talking machine cabinet having a hinged cover, an open-ended box-like member for holding records adapted to be housed in said cover, means pivotally mounting said record holding member in said cover including an L-shaped member, a pin projecting from one of the arms of said member, and a slotted bracket on said cabinet cooperating with said pin to produce relative movement between said record holding member and said cover.

5. The combination of a talking machine cabinet having a hinged cover, an open-ended box-like member for holding records adapted to be housed in said cover, an L-shaped member mounted on said record holding member, means pivotally mounting said record holding member including a pivot means coacting with said L-shaped member, a pin carried by one of the arms of said L-shaped member, and a slotted bracket on said cabinet cooperating with said pin to produce relative movement between said record holding member and said cover.

In testimony whereof I have signed this specification.

THOMAS T. GREENE.
